UNITED STATES PATENT OFFICE.

BERNARD C. BECKER, OF YORK, PENNSYLVANIA.

CLASP FOR PENCILS.

Application filed November 18, 1922. Serial No. 601,697.

This invention relates to clasps for lead pencils or the like, the purpose of which is to attach said pencil to the edge of a garment pocket.

5 The object of this invention is to provide a clasp which normally tends to recede and lie substantially flush with the surface of the body of the pencil.

10 A further object is to provide a clasp which grips the garment throughout substantially its whole length; the object of this extensive gripping action is to render the clasp effective in holding the pencil firmly in the position at which it is fixed.

15 Other objects will be apparent from the following description, taken in connection with the accompanying drawing, forming a part hereof, and in which similar numerals refer to similar parts throughout the several views.

20 Fig. 1, is a side elevation of a pencil, the same being shown partially in section to disclose the detail construction of one form of my invention.

25 Fig. 2, is a front elevation of Fig. 1.

Fig. 3, is a reproduction of the principal elements shown in Fig. 1, but shown in the position as when gripping the edge of a garment.

30 Fig. 4, is a sectional view of Fig. 3, taken on line 4—4.

Fig. 5, represents a modified form of my invention.

35 Fig. 6, is another modified form of my invention.

In carrying out my invention I form a cavity or groove 6 in the side of the pencil 7, and provide a clasp 8 which is adapted to close said cavity in substantially true

40 form with the surface of the pencil. In the cavity 6 is a spring 9 which is fixed at one end of the pencil 7 through the rivets 10, and the other end to the clasp 8 through the rivets 12. The one end of the spring 9 is bent to return upon itself as shown at 11, thereby forming a resilient gripping device for gripping the garment as shown at 20. Through the normal action of the spring 9, the garment 19 is also gripped by the clasp 8 at the point 21, and along the greater part of its length in the manner as shown at 23, Fig. 4.

45 A button 14 is fixed to the clasp 8 and adapted to contact with the bottom of the cavity 6, when the clasp is substantially

flush with the surface of the pencil as shown in Fig. 1. A positive bend in the spring 9 as shown at 18 is provided to maintain the end 32 of the clasp substantially flush with the surface of the pencil, and also to 60 form a fulcrum upon which the clasp 8 turns when pressure is applied at the end 32 in the direction indicated by the arrow 16. When pressure is applied in this manner the clasp takes the position as shown in light broken lines indicated by 8'; and when in this position it is adapted to be slipped over the edge of a garment to grip the same as shown in Fig. 3. For releasing the clasp from the garment 19, it is simply 65 a matter of gripping the head end 24 of the pencil and slipping the clasp from the garment; the spring 9 being sufficiently yielding to permit such action.

70 With reference to the modified form shown in Fig. 5, the clasp 8 is here hinged to the link 26 through the pin 25; the link 26 being also hinged to the block 28 through the pin 27. The clasp 8 carries a hook 33, and through the spring 30 being adapted to apply pressure on this hook in the direction indicated by the arrow 31, the entire mechanism is normally held in the position as shown. The spring 30 and the block 28, of course are fixed to the body of the pencil 7 75 through the tacks 29. In this device it is apparent that if pressure is applied on the end 32 of the clasp 8, and in the direction indicated by the arrow 16, the opposite end 17 will rise out of the cavity 6 to permit insertion of the edge of the garment. The general clasping action of this device is substantially the same as that described with reference to Figs. 3 and 4.

80 With reference to the modified form shown in Fig. 6, this device consists of a simple spring wire 53, fixed in the pencil body 7 at 34, and adapted to close the cavity 6 substantially flush with the surface of the pencil as shown. It is apparent in this construction 85 that if pressure is applied on the end 32, and in the direction indicated by arrow 16, the end 17 will rise out of the cavity to permit insertion of the edge of the garment. The general gripping action of this device is substantially the same as that described with reference to Fig. 5 and Figs. 3 and 4.

90 To facilitate the pressing in of the end 32 of the clasp 8, a button may be fixed to the clasp as shown at 15.

Having thus described my invention, what I claim, and desire to secure by Letters Patent is as follows:

1. The combination of a pencil having a cavity in the side thereof, and a garment clasp in said cavity, said clasp being arranged to close said cavity in a manner substantially flush with the surface of said pencil and capable of opening to grip the garment, when pressure is applied thereto while it lies within said cavity.
2. The combination with a pencil having a cavity in the side thereof, of a garment clasp in said cavity, and resilient means carried by the pencil which normally tends to draw said clasp into said cavity and thereby clamp the garment.
3. The combination with a pencil having a cavity in the side thereof, a garment clasp in said cavity, and resilient means which normally tends to draw said clasp in said cavity, said resilient means in conjunction with said clasp being arranged to form a secondary clasp also suitable for gripping a garment.
4. The combination of a pencil having a cavity in the side thereof, a garment clasp in said cavity, a fulcrum upon which said clasp will tip and arranged whereby the one end of said clasp will raise out of said cavity

when pressure is applied at the opposite end thereof, and resilient means which tends to hold said clasp against tipping.

5. The combination of a pencil having a cavity in the side thereof, a garment clasp in said cavity, a fulcrum upon which said clasp will tip and arranged whereby the one end of said clasp will raise out of said cavity when pressure is applied at the opposite end thereof, resilient means which tends to hold said clasp against tipping, and resilient means which tends to draw said clasp into said cavity.

6. The combination of a pencil having a cavity in the side thereof, a garment clasp in said cavity, and a fulcrum upon which said clasp will tip and arranged whereby the one end of said clasp will raise out of said cavity when pressure is applied at the opposite end thereof.

7. The combination of a pencil having a cavity in the side thereof, a garment clasp in said cavity, a fulcrum upon which said clasp will tip and arranged whereby the one end of said clasp will raise out of said cavity when pressure is applied at the opposite end thereof, and a button carried by the clasp at said opposite end.

In testimony whereof I affix my signature.
BERNARD C. BECKER.
